UNITED STATES PATENT OFFICE

2,113,347

MUSICAL INSTRUMENT

Frederick A. Hoschke, South Haven, Mich.; Wilhelmina Hoschke, executrix of Frederick A. Hoschke, deceased, assignor to Wilhelmina Hoschke, South Haven, Mich.

Application April 14, 1936, Serial No. 74,376

5 Claims.

(Cl. 84—1)

My invention relates to improvements in musical instruments of the electronic type, and it consists in the combination, constructions, and arrangements herein described and claimed.

5 An object of my invention is to provide an improvement over that set forth in my prior Patent No. 2,015,014, dated September 17, 1935. In said prior patent an electronic musical instrument was disclosed in which a reed in vibration formed 10 a portion of one plate of a microphone condenser, the other plate having means for adjustment with respect to the reed for varying the capacitance of the condenser.

The present invention relates to an improvement 15 in which the reeds themselves do not form a portion of the plate of the microphone condenser but in which diaphragms are provided, these diaphragms forming portions of one plate of the microphone condenser and in which means is provided for adjusting the other plate 20 inductively with respect to the diaphragms.

An object of the invention is to provide a construction which is particularly adapted to the "picking up" of all of the harmonics that are 25 caused by the shape or the bending (prevoicing) of a reed particularly of the higher harmonics.

A further object of the invention is to provide 30 a simple device by means of which condenser microphone diaphragms are provided which respond to compressed and rarified air impulses in strict pneumatic fashion.

Other objects and advantages will appear in 35 the following specification and the novel features of the invention will be particularly pointed out in the appended claims.

My invention is illustrated in the accompanying drawings, in which:

Figure 1 is a transverse sectional view through 40 a portion of the instrument along the line 1—1 of Figure 2, the amplifying circuit being shown in diagram.

Figure 2 is a plan view of the device along the line 2—2 of Figure 1, the amplifying circuit being omitted.

45 Figure 3 is an enlarged sectional view along the line 3—3 of Figure 1.

Figure 4 is a vertical sectional view along the line 4—4 of Figure 1.

50 Figure 5 is a sectional view showing a modified form.

Figure 6 is an enlarged sectional view along the line 6—6 of Figure 5.

55 Figure 7 is a sectional view of a portion of a modified form of the device, and

Figure 8 is a sectional view of a portion of another modified form of the device.

In carrying out the invention I make use of structure which is to be found in the ordinary reed organ. Referring particularly to Figure 4 5 I have shown therein a wind chest 1, a reservoir or wind pressure regulator 2 having openings 3 for a suitable suction wind supply. The top part of the wind chest is formed by a pallet board 5 (see Fig. 1). On the underside of the pallet board are pallets or valves 6 which are provided with a felt covering 7. It will be understood 10 that there is a pallet for each key. Each pallet is normally held in the position shown in Figure 1 by means of a spring 8 carried by the pallet 15 board and is guided by pins 9 which extend through slots 10 at each end thereof. In Fig. 1 I have shown a single key 11, of the keyboard 20 of the instrument, which is arranged to bear on a dowel 12 that passes through an opening 13 in the pallet board 5 for depressing the pallet or valve.

Mounted on the pallet board 5 is a cell section 14 having a series of partitions 15 for forming cells. As will be seen from Figure 4 the 25 walls of the partitions are slotted to receive the frames 16 which bear the reeds 17, the latter being secured in any suitable manner such as by rivets, as shown in Figure 1, each reed being disposed over a slot 18 in the frame. The pallet board 5 has slots 19 which register with the slots 18 and the bottoms of these slots 19 are normally 30 closed by the pallets 6.

The top 14^a of the cell section 14 is provided 35 with openings 20 above each cell. An insulating block 21 (see Fig. 1) is provided for each reed or cell, that form of the block shown in Fig. 1 having a recess 22 into which the end of a screw 23 extends, the screw being threaded into the block. A nut 24 is carried by the screw for locking the latter in its adjusted position. The block 21 is held to the top 14^a of the cell section 14 in any suitable manner such as by screws 25.

As stated there is an adjustable screw for each 45 diaphragm. The insulating blocks are arranged side by side as shown in Fig. 2 and a conducting strip 26 of tin foil or duralumin foil is disposed over the openings 20 and is held in taut position by means of the insulating blocks 21. This provides a thin diaphragm of foil over each 50 opening 20 and underneath the enlarged end of each screw 23.

The nuts, such as those shown at 24, not only 55 serve for locking the screws 23 in adjusted position, but they also serve to clamp a conducting

strip 27 (see Fig. 2) to the tops of the insulating blocks 21.

The conducting strip 27 is connected by means of a conductor 28 with the grid 29 of a suitable tube of a preamplifier. The foil plate 26 which forms the diaphragms 26^a is connected by means of a conductor 30 with the battery B of the radio circuit shown in Fig. 1. It will be understood that this is simply a typical circuit and forms no part of the present invention except as such circuit is used in connection with the apparatus for producing a tonal effect by the adjustment of the apparatus as presently described.

Consider now Figure 1. Let us assume that the key 11 is depressed and that through the medium of the dowel 12 and the pallet 6, communication is established between the cell section above the reed and the suction wind chest. Air entering the front end of the cell cavity is allowed to pass the reed which vibrates within the cell according to the frequency (fundamental and harmonics) of the reed. The constants of such fluctuation are determined by the nature of the air puffs caused by the movement of the reed, different shaped and "voiced" reeds causing different constants. The small diaphragm 26^a in the ceiling of the cell cavity is therefore responsive to these fluctuations. Now these small diaphragms, which are all connected together, form portions of one plate of the microphone condenser and the screws which are electrically connected together form the opposite plate of the microphone condenser. The impulses are conveyed to a pre-amplifier, then further amplified and converted into sound in the loud speakers.

The entire control of tone quality rests in the prevoicing of the reed. The reed itself is out of the electric or electronic circuit and acts merely as a pneumatic valve. This arrangement differs from the conventional radio studio microphone in that the small diaphragms in the insulating units do not respond to sound waves like the conventional radio studio microphones do but rather to variations of the air flow or pressure controlled by the reeds. It is not the reed that makes the tone; it is the air puffs.

As stated above the reed in most instances is first prevoiced. A reed which is not prevoiced gives a quality of tone which is characteristic of a flat vibrating reed. The ends of the reed may be bent as shown in my prior Patent 2,015,014 to alter the tone quality to produce such effects as flute tones, clarinet tones, etc. In adjusting the mechanism the nut 24 is loosened and the screw 23 is turned by means of pliers or any other suitable instrument so as to bring the lower end of the screw bearing the head into inductive relation with the diaphragm 26^a until the desired amplitude is attained.

Figures 1 and 2 show one means of mounting the metal foil plate 26. In these figures the plate is cemented to the top 14 of the cell section. Those portions of the plate which cover the openings 20 in the top portion 8 constitute the diaphragm.

In Figure 5 I have shown a modified form in which the foil plate 31 is held in position by an insulating block 32 of hard rubber or the like. This block has a cylindrical boss 32^a of slightly smaller exterior diameter than the opening which corresponds to 20 in the top 14^a of the cell section. The foil diaphragm is placed on top of the member 14 and the insulating block 32 is forced downwardly, the boss 32^a entering the opening

and stretching the diaphragm tightly as shown at 31^a. The block is then screwed to the top 14^a and the adjustment of the screw 23 is made as before stated. In this instance, the diaphragm 31^a is below the top 14^a as distinguished from that form shown in Figure 1.

In Figure 7 I have shown a modified form in which one diaphragm covers two cavity cells instead of one, thereby reducing the diaphragms and tone screws to one-half their number. Thus in the figure the cell section 14 and the cell cavities 14^a are in direct communication by means of a bore 35 with the diaphragm 36 which spans the recess 37 in the insulating cover 38. The head of the tone screw 39 is disposed in the recess 15 and the screw is held in position by the lock nut 40.

In this form of the device it will be observed that the tone screw is spaced symmetrically with respect to the reeds 41 and 42 so that the diaphragm covering the recess 37 is directly affected by the puffs of air generated by the vibration of both or either of the reeds 41 and 42.

In Figure 8, which is another modification, a block of wood 43 may be secured at any point in the wind chest on a mounted base 44. The block 43 has a recess 45 which is open to the atmosphere within the wind chest. A diaphragm 46 is stretched over this recess and over a recess 47 in an insulating block 48 having a tone screw 49. 30

Every time a pallet is opened by pressing a key a reed goes into vibration. In swinging back and forth the reed opens and closes the atmospheric current tending to pass the reed, thus creating impulses, these impulses having an effect 35 upon the entire wind supply within the chest, expanding and contracting its contents or distributing the movement thereof to a degree sufficient to agitate a single diaphragm such as that shown at 46.

Such a simple diaphragm would not have the amplitude of one with each cell or two cells but this is compensated for by using additional tone screws over it, thereby increasing the pick-up. The close proximity between the tone screw and 45 the diaphragm increases the tension of the electrostatic charge so that additional tone screws will increase the charge, as desired.

By setting or fastening such a unit at or to the bottom, sides or top of the wind chest (inside 50 of the latter) the diaphragm will pneumatically respond to air fluctuations caused by the swinging reed or reeds. A conductor 50 connects the tone screw 49 with the grid 29 (see Figure 1) while a similar conductor 51 connects the dia- 55 phragm to the B battery.

In the use of the device shown in Figure 8 individual diaphragms may be dispensed with although it will be understood that my preferred form is that in which individual diaphragms are used.

I claim:

1. In a musical instrument, a plurality of reeds, each reed being disposed in an individual cell cavity, pneumatic means for selectively vibrating said reeds, a diaphragm associated with each cell cavity and adapted to be oscillated by pulsations of air from its vibrating reed, an adjustable conductor associated with each diaphragm on the opposite side thereof from the 70 reed, said diaphragms being in electrical connection to form one plate of the microphone condenser, and said conducting members being in electrical connection with one another to form the opposite plate of the condenser.

2. In a musical instrument, a plurality of pre-voiced reeds, each reed being disposed in an individual cell cavity, pneumatic means for selectively vibrating said reeds, a diaphragm associated with each cell cavity and adapted to be oscillated by pulsations of air from its vibrating reed, an adjustable conductor associated with each diaphragm on the opposite side thereof from the reed, said diaphragms being in electrical connection to form one plate of the microphone condenser, said conducting members being in electrical connection with one another to form the opposite plate of the condenser, and an amplifying circuit working in conjunction with said microphone circuit. 5
3. In a musical instrument, a cell section having individual reed cavities, a reed associated with each cavity, each of said cell sections having an opening opposite the reed, a thin metal strip covering said openings, that portion of the strip spanning the openings constituting a diaphragm for its associated cavity, and an insulating block having recesses on the opposite side of the diaphragm corresponding to the openings of the cell cavities, thereby affording space for the movement of the diaphragms away from the reeds. 10
4. In a musical instrument, a cell section having individual reed cavities, a reed associated with each cavity, each of said cell sections hav- 15
- ing an opening opposite the reed, a thin metal strip covering said openings, that portion of the strip spanning the openings constituting a diaphragm for its associated cavity, an insulating block having recesses on the opposite side of the diaphragm corresponding to the openings of the cell cavities, thereby affording space for the movement of the diaphragms away from the reeds, means for securing the block to the cell section whereby the metal strip is clamped in position, and an adjustable conductor disposed in each recess, said adjustable conductors being in electrical connection and forming one plate of a microphone condenser, and said metal strip forming the other plate. 20
